UNITED STATES PATENT OFFICE.

JOSEPH M. MERROW, OF HARTFORD, CONNECTICUT, ASSIGNOR TO THE MERROW MACHINE COMPANY, OF HARTFORD, CONNECTICUT, A CORPORATION OF CONNECTICUT.

TRIMMING-CUTTER FOR SEWING-MACHINES.

No. 907,621.

Specification of Letters Patent.

Patented Dec. 22, 1908.

Application filed December 9, 1905. Serial No. 291,134.

To all whom it may concern:

Be it known that I, JOSEPH M. MERROW, a citizen of the United States, residing in the city and county of Hartford, State of Connecticut, have invented certain new and useful Improvements in Trimming-Cutters for Sewing-Machines, of which the following is a full, clear, and exact description, reference being had to the accompanying drawings, 10 forming a part of this specification, and to the figures and letters of reference thereon.

This invention relates to trimming cutters its principal object being to provide a reversible cutter having a cutting edge at each 15 end and an adjacent guide or finger each cutting edge and its guide or finger being capable of being ground or sharpened in a single plane and each cutting edge being also capable of being ground or sharpened independently of 20 the guiding finger.

The cutter as shown is well adapted for use in sewing machinery to trim off the edges of the material.

In the accompanying drawings—Figure 1 25 is a side elevation of the cutter, clamped to its support or carrier and shows also a portion of the companion cutter. Fig. 2 is a front elevation of the parts shown in Fig. 1. Fig. 3 is a sectional view taken on the line 30 3—3 of Fig. 2. Fig. 4 is a front elevation of the cutter detached. Fig. 5 is a side elevation of the cutter as seen from the left of Fig. 4. Fig. 6 is a side elevation of the cutter as 35 seen from the right of Fig. 4. Fig. 7 is a plan view of the cutter as seen from above Fig. 4.

Similar letters of reference indicate like parts throughout the several figures of the drawings.

40 The cutter A is preferably made from a flat or rectangular steel bar, bent at an obtuse angle at each end in counter fac-simile, thereby forming a shank portion a and a relatively short limb a' at each end, each limb being at an angle to the longitudinal axis of the shank. Each limb is cut away 45 diagonally for a portion of its length and with the outer end forms a cutting edge as at a² and a guide or finger a³ for each cutting 50 edge, the effect of such cutting away at the ends of the limbs being to leave a comparatively small flat surface a⁴ at either end which may be ground together with the face of the guide or finger in a single plane to

55 sharpen the cutting edge and overcome the effect of wear. The cutter may also be sharpened by grinding the diagonal face a⁵ at either end instead of grinding the faces or surfaces a⁴ a⁴ as may sometimes be preferable, especially when the side of the guide or 60 finger has not become worn, but the cutting edge has become dull.

The diagonal cuts across the short limbs are both made upon the same edge of the bar and each of the bevels or faces a⁵ is preferably made at an acute angle with its corresponding flat face a⁴ while each of the cutting edges is preferably made at an obtuse angle to its corresponding finger a³.

The cutter is adjustably clamped to its 70 support or carrier B by the clamp D and the clamp screw E and it will be understood that the companion cutter is secured to some portion of the machine and that one of the cutters is suitably moved in a path approximately parallel to the acting face of the cutter A and the face or side of the companion cutter C by any known or suitable means. Ordinarily the cutter A is the moving cutter.

It will be apparent that the cutter A, after 80 having become dull at one of its cutting edges may be reversed or turned end for end and the opposite end brought into use.

Having thus described my invention, what I claim as new and desire to secure by Letters Patent, is:—

1. A cutter, bent at its opposite ends to form a limb at each end, each limb being formed with a cutting edge and a guide or finger therefor, the faces of the two limbs 90 being in separated substantially parallel planes and the two edges of the cutter being also in substantially parallel planes, substantially as described.

2. As an article of manufacture, a trimming cutter formed with a straight body portion and a limb at each end at an angle to said body portion, the faces of the two limbs being in substantially parallel planes and the two edges of the cutter being also in substantially parallel planes, each of the said limbs 100 being formed with a cutting edge and a guide or finger, substantially as described.

3. As an article of manufacture, a reversible trimming cutter with a limb at each end 105 at an angle with the main or body portion of the cutter, the faces of the two limbs being in substantially parallel planes and the two

edges of the cutter being also in substantially parallel planes, each limb being provided with a cutting edge and a guiding finger so disposed that one face of each limb may be 5 ground in a single plane to sharpen the cutting edge and include one side of the guiding finger, substantially as described.

4. As an article of manufacture, a cutter bent at both ends forming a limb at each end, 10 the faces of the two limbs being in substantially parallel planes and the two edges of the cutter being also in substantially parallel planes, each limb being formed with a cutting edge and a guiding finger having their 15 outer faces in the same plane and each of which faces may be ground in a single plane to sharpen the cutting edge and include the face of the guiding finger, both of the guiding fingers being located upon the same edge 20 relative to the shank or body portion of the cutter, substantially as described.

5. A cutter having a shank or body portion and a limb at one end at an angle to the body portion, said limb being provided with 25 a cutting edge and a finger, the cutting edge lying in the plane of one face of the finger,

said plane being oblique to the body portion of the cutter, substantially as described.

6. A cutter embodying a substantially straight body portion and end portions or 30 limbs bent at an angle thereto, the faces of the two limbs being in substantially parallel planes and the two edges of the cutter being also in substantially parallel planes, said limbs each being formed into a cutting edge 35 and a guide or finger projecting beyond said edge, one face of the guide finger and the cutting edge being in a single plane, substantially as described.

7. A cutter embodying a substantially 40 straight body portion and end portions bent at an angle thereto in opposite directions and in substantially parallel planes and the two edges of the cutter being also in substantially parallel planes, the said end portions 45 each being formed into a cutting edge and a guide or finger therefor projecting beyond the cutting edge, substantially as described.

JOSEPH M. MERRROW.
